UNITED STATES PATENT OFFICE.

ADOLPH ROSNER, OF SPRINGFIELD, MASSACHUSETTS, ASSIGNOR TO AMERICAN BOSCH MAGNETO CORPORATION, OF SPRINGFIELD, MASSACHUSETTS, A CORPORATION OF NEW YORK.

MAGNETO.

Application filed December 7, 1921. Serial No. 520,702.

To all whom it may concern:

Be it known that I, ADOLPH ROSNER, a citizen of the United States, residing at 4 Ventura Street, Springfield, in the county 5 of Hampden, State of Massachusetts, have invented certain new and useful Improvements in Magnetos; and I do hereby declare the following to be a full, clear, and exact description of the invention, such as 10 will enable others skilled in the art to which it appertains to make and use the same.

The present invention relates to magnetos of the oscillating type and more particularly 15 to the oscillating mechanism thereof.

It was customary, heretofore, to provide this type of magneto with a pair of helical springs which were fastened over rollers on the oscillating trip lever and over rollers 20 on studs extending laterally from the frame of the magneto. These springs extended outwardly a considerable distance and require a good deal of space for installation. Moreover, it was difficult to lubricate and protect 25 the relatively movable parts thereof to eliminate excessive wear. In some cases the helical springs were disposed co-axially of the oscillator shaft with the ends of the springs reacting between a fixed part of the magneto frame and the trip lever. In both 30 types of construction, the springs had no support, but were held in position by their ends only, through which the flexing stresses were effective.

35 In accordance with this part of my invention, the oscillating mechanism of the magneto has a spring which is disposed in a plane transverse to the axis of the oscillator and preferably in a plane parallel 40 to the plane of oscillation of the trip lever.

The spring also preferably surrounds the shaft of the oscillator. The ends of the spring act in this plane and normally press 45 against a fixed part of the magneto. The trip lever is operative, preferably owing to the lever extending between such ends of the spring, to press against either end of the spring to strain it in either direction of oscillation of the trip lever. A housing

50 which is rigid with the frame of the magneto, by fastening it to such frame, may also be provided for the springs. Such housing is preferably made of pressed-up sheet metal, and has an annular channel in which 55 the springs are located, the springs being

preferably protected by a cover plate. Such housing may also have lubricating means for supplying a lubricant, by gravity, to the springs, as well as to the bearing of the oscillator. A drain opening is also preferably provided in the housing for drainage of the excess lubricant. The spring may be arc-shaped, but preferably is substantially circular, and it may be formed from a plurality of superposed springs 60 which are preferably arranged in a concentric relation. In order to support the springs and to distribute the actuating stresses thereto, the magneto is provided with an expandable member, preferably in 65 the form of half rings which are in mutual engagement at one end thereof and normally contacting with a fixed part of the frame of the magneto at the other end thereof. These half rings, the springs and the trip lever 70 are so related that the lever is operative to move either of the half rings in either direction of oscillation of the lever to strain the springs. By such structure the oscillating mechanism occupies less space and is 75 in a more protected condition than in prior constructions. The spring also operates to more suddenly oscillate the oscillator, thus effecting a better sparking action, and it is more nearly "dead beat" or has a greater 80 dampening effect on the oscillating parts than the springs of prior constructions. The half rings act to distribute the forces along the springs and also aid in effecting the dampening mentioned. Greater force 85 may be imposed upon the springs without danger of breaking them.

In the accompanying drawing illustrating my invention in application, as an example, to a magneto of the oscillating type: 90

Fig. 1 is an end view of the magneto; Fig. 2 is a longitudinal sectional view through the oscillating mechanism and the end of the magneto; Fig. 3 is a similar view of a modified construction; Fig. 4 is 95 a transverse sectional view of the oscillating mechanism; Fig. 5 is a similar view showing the parts in a different position of operation; and Fig. 6 is an end view of the magneto showing the mode of selectively 100 mounting the oscillating mechanism.

Such magneto comprises a frame 1 of cast metal, such as aluminum, and an oscillator 2 having a shaft 3, supported in a bearing 4, the latter being fastened into the flanged 110

- 2
- end 5 of the frame 2 by means of screws 6, as is clearly shown in Fig. 2 of the drawing. The outer end of the shaft has a tapered portion 7 to which is secured a trip lever 8 comprising a yoke portion 9 having a tapered bore to fit with the tapered portion 7 of the shaft. The trip lever 8 is held in position on the shaft by a lock washer 10 and a nut 11 threaded upon the threaded end 12 of the shaft and is non-rotatably fastened to the shaft by means of a key 13. Between the oscillator and the shaft portion 3 is provided a collecting ring 14 with which may cooperate a collector brush, (not shown).
- 15 At the end of the frame is connected a pressed-up sheet metal housing 15, which is of annular shape, so as to provide an annular channel 16, within which is located a pair of half rings 17 and 18 and a group of springs 19, surrounding such half rings. The housing 15 is secured to the frame 1 by screws 20, as is clearly shown in Fig. 4 of the drawing. The inner flanged portion 21 of the housing fits over a hub portion 22 forming an integral part of the frame 1, and the half rings 17 and 18 fit about the flanged portion 21. The bearing 4 fits within this hub portion, as is clearly shown in Fig. 2 of the drawing.
- 20 At the top of the housing may be located an oil cup 23 from which a lubricant may be supplied by gravity to the springs 19 and the half rings 17 and 18, as well as to the bearing 4, the excess oil, flowing to the bottom of the housing, escaping through a drain opening 24. For the purpose of supplying oil to the bearing 4, the housing 15 is formed with an opening 25 for facilitating the passage of the oil to bores 26 and 27, respectively, provided in the hub portion 22 and the bearing 4, as is also clearly shown in Fig. 2 of the drawing.
- 25 The outer end of the housing is closed by a cover plate 28 which is secured by bolts 29 to the yoke portion 9 of the trip lever 8. At the lower end of the housing 15 and within the annular space 16 is located a block 30 which is held rigid with the outer flange 31 of the housing 15 by means of a hollow rivet 32, the passage through the rivet 32 forming the drain opening above mentioned. The half rings have downwardly extending ends 33 and 34 located on the opposite sides of and normally in contact with the block 30, the latter acting as a stop or abutment means for the ends 33 and 34. The other ends 35 and 36 of the half rings are in mutual contact at a point in a vertical plane substantially coincident with the axis of the oscillator. The trip lever also carries an inwardly extending projection 37 located between the ends 33 and 34 of the half rings and above the stop block 30. The springs are substantially circular in form or arc-shaped, with their ends
- 30 extending toward and capable of contacting with the end portions 33 and 34 of the half rings. The ends of the springs are slightly bent to aid the sliding and the bending action of the springs when strained during the operation of the magneto. It will be noted that these springs are arranged in concentric relation and are of the same length and surround the half rings to normally hold the end portions 33 and 34 against the stop block 30 and the upper ends 35 and 36 in mutual contact.
- 35 In operation, the trip lever is oscillated by a moving part of an engine, so as to move the trip lever in either direction of oscillation about the axis of the shaft of the oscillator. Depending upon the direction of oscillation of the trip lever, the projection 37 engages with either the end 33 or 34, and causes either the half ring 17 or 18 to move about the end 35 or 36 as a fulcrum and to strain the springs 19. As the actuating member of the engine disengages from the lower end of the trip lever 8, the springs 19 suddenly react to return the half ring 17 or 18 to its normal position, and to oscillate the trip lever together with the oscillator. Hence, the oscillator is given a sudden angular impulse during which the magnetic flux is reversed and a spark effected at the interrupter contacts. During such reaction or contraction of the springs 19, the half ring 17 or 18 is brought to a stop against the stop block 30, and the trip lever impacts with the other end 34 or 33, as the case may be. Such impact is absorbed by the ends of the springs reacting against such end portions 34 or 33 of the half rings, and the trip lever together with the oscillator, is quickly brought to normal position. It will thus be observed that the oscillating mechanism is double acting, capable of oscillating in either direction of oscillation, without making any change whatever in arrangement of parts of construction.
- 40 In Fig. 3 of the drawing is shown a modified construction in which the frame 1 has an integral extension 38 forming the housing for the springs 19 and the half rings 17 and 18. In this construction the trip lever is riveted to the cover plate 39 and the latter has at its lower end an inwardly extending projection 40, corresponding to the projection 37 of the trip lever shown in Fig. 2 of the drawing. The housing 38 has an integral stop block 41 against which the ends 33 and 34 of the half rings come to rest, and the projection 40 extends between the ends 33 and 34, similar to the projection 37 of the trip lever 8 of the form shown in Figs. 3 and 4 of the drawing.
- 45 In Fig. 6 is shown a mode of selectively mounting the trip lever in one of several different positions. It will be noted that the housing 15 is connected to the end of the

frame 1 by four screws which are equally distant, such that the housing carrying the oscillating mechanism and the trip lever as a unit, may be turned in any one of four 5 different positions, and connected in such position by screws 20. It will thus be observed that the trip lever may extend vertically downwardly or upwardly or laterally to the left or right, as is shown in the full 10 and dotted line positions of the trip lever in Fig. 6 of the drawing.

In Fig. 5 the mechanism is shown in strained condition, where the trip lever has been moved to a point just prior to its 15 release and reaction of the springs for oscillating the trip lever and oscillator.

Having thus described my invention, what I claim is:

1. A magneto comprising a frame, an oscillator, a generating winding, an oscillatory trip lever fastened to said oscillator, and a plurality of superposed arc-shaped springs having the opposite ends of said springs normally pressing against a fixed part of said 20 frame, said lever extending between said ends of said springs and being operative to press against either of said ends of said springs to strain said springs in either direction of oscillation of said lever.

2. A magneto comprising a frame, an oscillator, a generating winding, an oscillatory trip lever fastened to said oscillator a

spring for oscillating said trip lever, an expandible member for straining said spring in either direction of oscillation of said trip 35 lever, said trip lever being operative to expand said member.

3. A magneto comprising a frame, an oscillator, a generating winding, an oscillatory trip lever fastened to said oscillator, a pair 40 of movable strain members being in mutual engagement at one end of said members and normally in contact with a fixed part of said frame at the other end of said members, a spring normally holding said members in contacting position, said trip lever being operative to move either of said members in either direction of oscillation of said trip lever to strain said springs.

4. A magneto comprising a frame, an oscillator, a generating winding, an oscillatory trip lever fastened to said oscillator, a pair 45 of half rings being in mutual engagement at one end of said rings and normally in contact with a fixed part of said frame at the other end of said rings, a spring normally holding said half rings in contacting position, said trip lever being operative to move either of said half rings in either direction 55 of oscillation of said trip lever to strain 60 said springs.

In testimony whereof I affix my signature.

ADOLPH ROSNER.
